UNITED STATES PATENT OFFICE.

WILLIAM RUSH OSBORNE, OF PALESTINE, AND GEORGE FRANKLIN LEBUS, OF ELECTRA, TEXAS.

WELL-DRILL WRENCH.

1,053,931.

Specification of Letters Patent.

Patented Feb. 18, 1913.

Application filed August 27, 1912. Serial No. 717,376.

To all whom it may concern:

Be it known that we, WILLIAM RUSH OSBORNE and GEORGE FRANKLIN LEBUS, citizens of the United States, and residents, respectively, of Palestine, in the county of Anderson and State of Texas, and Electra, in the county of Wichita, in said State, have invented an Improvement in Well-Drill Wrenches, of which the following is a specification.

Our invention is an improvement in the class of large pipe wrenches which are particularly designed and adapted for use on drill pipe used in drilling wells, the pipes being made in sections which are connected in vertical alinement by means of screw couplings. Great force is often required to unscrew the sections, for the purpose of renewing the boring bit, as may be required several times in the course of a day's work.

The details of construction, arrangement, and operation of the wrench is as herein-after described, and illustrated in the accompanying drawing, in which—

Figure 1 is a plan view of the main portion of the wrench applied to a drill pipe shown in cross section. Fig. 2 is a side view of the same parts shown in Fig. 1. Fig. 3 is a perspective view of the wrench 30 with the jaws open.

The chief components of the wrench are two curved jaws 1, 2, a handle and lever 3, parallel links 4, and a hasp or clutch member 5 which serves to lock together the free ends of the jaws. The main jaw 1 is pivoted at 6 directly to the end of the handle and lever 3, and provided with a detachable segmental gripping block 7, which is provided on its inner surface with ratchet 40 teeth, or transverse ribs, inclined in a direction away from the pivot. The inner end of this gripping block abuts a shoulder 1^a formed at the heel, or inner end, of the jaw, and such shoulder serves to resist the pressure on the gripping block which is incident to operation of the wrench. Lag screws 8 pass through the jaw 1 and secure the block 7 in place.

As shown in Fig. 3, the inner or toothed side of the block is provided with grooves into which the ends of the screws project. The opposite or smaller jaw 2 is pivoted at 9 between two flat parallel links 4, which are formed at an obtuse angle and pivoted 55 to the lever 3 at 10, that is to say, at a point

in rear of the pivot 6 of the main jaw. A toothed gripping block 7^a is applied to the jaw 2 and its outer end abuts a lug or shoulder 2^a, while a lag screw 11 secures it at the middle. Thus the lug 2^a resists endwise pressure of the gripping block which occurs in use of the wrench. The clutch member 5 is a curved and tapered bar and pivoted at 12 to the free end of the main jaw 1, while its free terminal is provided, as shown in Fig. 3, with a slot 5^a adapted to receive a lug 2^b formed integrally with the smaller jaw 2 and located adjacent to the end of the latter.

As shown in Figs. 2 and 3, the thickness of the pivoted end of the jaw 1 and the adjacent portion of the lever 3 is such that they are adapted to pass between the links 4 when the wrench is being operated, and thus we produce what may, in view of its operation, be termed a toggle pipe wrench, 70 since the gripping action of the jaws on the drill pipe increases corresponding to the pressure applied to the lever in the direction indicated by arrow. There is therefore 75 no danger of the jaws slipping on the pipe *a* in the operation of the wrench.

In unscrewing the drill pipe, the wrench, which is often termed "breaking-out tongs," is placed on the pipe above the coupling, it 80 being necessary for this purpose to open the jaws, as shown in Fig. 3, and then to engage them by means of the clutch, as shown in Figs. 1 and 2. Another wrench is placed on the coupling and engaged with a fixed 90 object on the turn-table; then the clutch member being thrown in and pressure applied to the lever 3, the pipe is rotated and thus unscrewed.

It is unnecessary to give other details of 95 the operation of the wrench save to state that, for the purpose of hoisting and lowering and otherwise conveniently operating the wrench, an eye-bolt 13 is screwed into the lever 3 at a point adjacent to the pivot 100 of the links 4, and a rope is connected with this and passed over a pulley or beam overhead.

What we claim is:—

1. The improved wrench for the purpose 105 specified, comprising a lever, two oppositely curved jaws, one pivoted directly to the end of the lever and the other to parallel links which are in turn pivoted to the lever in rear of the jaw pivot, toothed segmental 110

gripping blocks applied to the inner sides of the jaws, a clutch member pivoted to the free end of the main jaw and provided with a slot, the other jaw having a radial lug with which the clutch is adapted to engage detachably, as described.

2. The improved pipe wrench for the purpose specified, comprising two oppositely curved jaws, a lever to which one jaw is pivoted, links which are arranged parallel and connect the opposite jaw with the handle, the pivoted ends of the lever and main jaw being of less thickness than the distance between the links, so that they are

adapted to swing between the latter, and a 15 toothed clutch member adapted to engage and lock together the free ends of the jaws, as described.
